PUMP

Jeff Corydon and Rudy Lowe, Providence, R. I.,
assignors to Proportioneers, Inc., a corporation
of Rhode Island

Application May 27, 1938, Serial No. 210,858

2 Claims. (Cl. 103—150)

The invention relates generally to pumps, and more particularly to pumps of the diaphragm type adapted for pumping corrosive liquids.

Pumps of this character are often used for the proportional feeding of chemicals or reagents, such as hypochlorite, so that it is necessary to employ diaphragms made from rubber. Although such diaphragms are normally reinforced, frequent cracking or breakage of the prior diaphragms has been experienced.

The primary object of the present invention is, therefore, to construct a diaphragm pump of this character wherein such cracking, breaking or wear on the diaphragm is materially reduced.

Another object is to provide a new and improved pump diaphragm constructed to minimize wear on the diaphragm.

Other objects and advantages will become apparent from the following description, taken in connection with the accompanying drawings, in which:

Fig. 1 is a horizontal plan view taken through a diaphragm pump embodying the features of the invention.

Fig. 2 is a similar view looking upwardly to show the outlet opening of the pump chamber and showing the diaphragm in a different position.

Fig. 3 is a view similar to Fig. 2 showing the diaphragm advanced toward the left beyond the positions of Figs. 1 and 2.

Fig. 4 is a perspective view of the diaphragm.

For purposes of disclosure, we have illustrated in the drawings and will hereinafter describe in detail the preferred embodiment of the invention, with the understanding that we do not intend to limit our invention to the particular construction and arrangement shown, it being contemplated that various changes may be made by those skilled in the art without departing from the spirit and scope of the appended claims.

In the form chosen for disclosure herein the invention is embodied in a pump 10 of the general character described and claimed in our co-pending application, Serial Number 25,467, filed June 7, 1935, now Patent No. 2,145,566, dated January 31, 1939. As herein shown the pump 10 comprises a main base or frame member 11 upon which a pump body or head 12, a pump diaphragm 13 and a diaphragm-actuating rod 14 are operatively mounted and associated.

The frame member 11 is preferably formed from a rigid casting to provide an operating opening 15 through which the actuating rod 14 extends, there being a recess or clearance chamber

16 at one end of the opening 15, with an annular flat or planar mounting surface 17 bordering the clearance chamber 16. Against the mounting surface 17 one face of the bordering edge portion 18 of the diaphragm 13 is positioned; and is held in place by clamping of the pump head 12 against its other face of the edge portion 18. Preferably the pump head 12 is of a form similar to that shown and claimed in our aforesaid application, and is secured in clamping relation to the bordering edge 18 of the diaphragm by similar means, this means including rigid clamping plate means 19 and clamping screws 20 extending through bordering portions 21 of the head 12, through holes 22 in the bordering edge portion 18 of the diaphragm and screwed into the rigid frame member 11.

To cooperate with the diaphragm 13 in forming a pump chamber, the pump head 12 has a recess 23 formed therein which opposes that portion of the diaphragm which lies inwardly of the clamped border portion 18 thereof. Since the chamber 23 is to be exposed to corrosive fluids, the pump head 12 is formed from a corrosion resistant material such as hard rubber. Proper clamping of the diaphragm 13 is assured by forming the pump head 12 so that its recess 23 is bordered by an annular surface 24, lying generally in a plane parallel to the opposed surface 17 of the mounting member 11, there being a projecting annular bead or ridge 25 on said surface 24 which is pressed into the diaphragm to produce a more perfect sealing action. The pump chamber 23, of course, has an inlet opening 26 (Fig. 1) and an outlet opening 27 (Fig. 2) which are controlled by suitable valves, (not shown) such, for example, as those shown and claimed in our aforesaid application.

The actuating rod 14, as herein shown, is connected to the diaphragm 13 so as to be detachable therefrom for the purpose of replacing the diaphragm. For this purpose a metallic push plate 30 is secured, as by a riveted connection 31, to the end of the rod 14 and within the pump chamber 23 a clamping plate 32 is provided whereby the center of the diaphragm may be clamped against the push plate 30. The clamping plate 32 as herein shown comprises a central metallic ring 33 from which a plurality of fixed studs 34 project. The ring 33 has a protective covering 35 of hard rubber or the like molded thereon; and the studs 34 project through holes 36 (Fig. 4) in the diaphragm, and through corresponding holes in the push plate 30. Nuts 37 on the studs 34 act to clamp the center of the

diaphragm in the desired relation to the plate 30; and it is to be noted that an annular sealing ridge 38 is provided on the covering 35 outside of the studs 34 so as to effectually seal and protect the studs against the corrosive fluid in the pump chamber 23.

Since the diaphragm 13 is subjected to the action of corrosive liquids, it is formed from a corrosion resistant flexible material such as soft rubber; and because of the pressures to which it is subjected the diaphragm 13 is reinforced as by means of a sheet 40 of fabric moulded in the rubber of the diaphragm. In accordance with the present invention the diaphragm and the associated parts of the pump are so formed as to avoid excessive wearing stresses on the diaphragm; and particularly so as to avoid stresses on reinforcing fabric which might tend to break the fabric, and to avoid tearing, cutting or breaking of the rubber of the diaphragm whereby to insure continued protection of the fabric from the corrosive liquid.

To this end the reinforcing fabric 40 is located midway between the two side faces or surfaces 25 of the diaphragm 13, and the diaphragm is performed or molded to provide an annular ridge or bead 41 of arcuate cross section located between the clamped central area 42 and the clamped bordering edge 18.

30 When mounted in its operating position, the diaphragm 13 is preferably located so that the bead 41 projects into clearance space 16 between the push plate 30 and the side wall of the space 16. Thus when the push plate is advanced to 35 the forward position of Fig. 3, there is no material stretching of the diaphragm 13 in a radial direction; and particularly there is no radial stretching of the diaphragm in the central region occupied by the reinforcing fabric 40. In 40 such advancing movement of the push plate 30, the rubber of the diaphragm 13 is stretched slightly on the left hand face of the diaphragm, and is slightly compressed on the right hand face, but in the median zone of the fabric 40 45 no tearing or stretching forces are exerted.

Similarly, when the actuating rod 14 is withdrawn, no material stretching forces are applied to the fabric 40, and the zones of compression and stretching of the rubber of the diaphragm 50 are reversed.

To prevent tearing or undue wear on the diaphragm in such actuation thereof, the various clamping elements acting on the diaphragm 13 are formed with rounded edges and supporting surfaces to engage the diaphragm wherever relative movement and contact takes place between such elements and the diaphragm. Thus the 55 push plate 30 has a receding border flange 50 with a rounded annular face 51 against which the outer surface of the bead 41 may engage 60 with a rolling action as the push plate is advanced from the position of Fig. 2, through the position of Fig. 1 and to the most advanced position of Fig. 3. In such advancing movement 65 the other face of the bead 41, adjacent the outer border portion 18, increases, with a rolling action, the degree or amounts of its contact with the bordering face 24 of the pump head 12.

In movement of the diaphragm in the other 70 direction from the position of Fig. 3, through the position of Fig. 1 and to the position of Fig. 2, the outer or right hand face of the bead 41 progressively, and with what might be termed a rolling action, engages an annular rounded 75 edge surface 54 formed between the side wall

of the recess 16 and the clamping surface 17 of the frame member 11. On the opposite or left hand face of the diaphragm, such retraction of the diaphragm causes rolling or progressive engagement of the diaphragm surface 5 with an annular rounded surface 55 formed on the clamping face of the covering 35.

The preformed pump diaphragm of the present invention is, of course, proportioned so that in the maximum pump stroke for which it is intended, there will still remain an appreciable curved formation in the cross sectional view of the diaphragm, as will be evident in Figs. 2 and 3. Thus radial tension or stretching forces are avoided in the fabric reinforcing, whereby 10 to increase materially the service life of the diaphragm. Moreover, the rolling or progressive engagement of the various associated or clamping parts with the faces of the diaphragm insures long wear, and prevents tearing, cutting 20 or premature cracking of these faces. It will be noted that in its pumping or exhaust stroke the diaphragm has a material portion of its area backed up by the flange 50 of the push plate, whereby to reduce the stress in the dia- 25 phragm 13 and thereby lengthen its useful life. This beneficial action of the push plate is particularly valuable where the pump is being used to inject the fluid against a high line pressure. Moreover, the contact of the diaphragm with 30 the push plate during the pumping stroke results in a smaller free or unbacked area in the diaphragm, and because of this it has been found that the present construction produces more uniform delivery volume than has heretofore been 35 obtainable with diaphragm pumps.

In its flexing from one position to another, it will be noted that the diaphragm of the present pump, regardless of the direction of shifting movement of the actuating rod 14, has a portion 40 which is preformed to a generally frusto-conical form so that in cross section it lies at an acute angle to the axis of the rod 14; and that in such movement this frusto-conical portion is moved toward a right angular relation to said axis. 45 Thus we may consider that portion of the bead 41 lying between the border 18 and the highest portion of the bead as such a frusto-conical portion, as shown in Fig. 1; and when the rod 14 is advanced to the position of Fig. 3, this 50 frusto-conical portion is moved toward a right angular relation to the axis of the rod 14. In such movement there is no stretching of this frusto-conical portion, and this action contributes to the long life of the diaphragm of the present 55 pump.

The inner half of the bead 41 may be considered as having a similar action when the diaphragm is flexed in the opposite direction from its normally preformed shape to the position of Fig. 2; and while the present pre-formed diaphragm provides for such non-wearing, non-stretching flexure in either direction from its normal preformed shape, it will be evident that by coordinating the pump stroke with form of 60 05 the diaphragm, one of these generally frusto-conical portions might suffice to attain in a measure the advantages and long life of the present construction.

We claim as our invention:

1. A pump of the character described comprising a rigid frame element having an annular clamping face, a flexible rubber diaphragm, a pump head recessed to cooperate with said diaphragm in forming a pump chamber, said head 70 75

and said frame element being clamped upon the border of said diaphragm, and an actuating rod secured to a predetermined area of the central portion of said diaphragm for flexing the diaphragm, said diaphragm being molded with an annular bead of arcuate cross section disposed inwardly of its clamped border, said annular bead being of a width extending from the clamped border to said predetermined area.

5 10. 2. A pump of the character disclosed comprising in combination, a mounting element having an opening and a bordering clamping face, a pump head having a recess bordered by a clamping face, a flexible rubber diaphragm having its border clamped between said clamping faces, an actuating rod extending through said

opening and having a push plate engaging the central portion of the adjacent face of said diaphragm, a clamping plate on the other side of said diaphragm and within said recess, means clamping said plates on said central portion of the diaphragm, said diaphragm being preformed with an annular bead located between and comprising the entire area intermediate said clamped areas of said diaphragm and projecting in a direction away from said recess, said push plate 10 having an edge flange extending along and backing up a substantial portion of the adjacent side of said annular bead during the discharge stroke of the pump.
